MAGNETIC SPEEDOMETER

Arden W. Le Fevre and Thorolf Paul, Chicago,
Ill., assignors to Stewart-Warner Corporation,
Chicago, Ill., a corporation of Virginia

Application January 17, 1936, Serial No. 59,567

6 Claims. (Cl. 264—13)

This invention relates to magnetic speedometers and its object is to provide a structure of this character which shall be relatively light in weight, with extremely simple mechanism and 5 with parts designed for economical manufacture and assembly. It consists of the features and elements of construction herein shown and described in combination, as indicated by the claims.

10 In the drawing:

Figure 1 is a face view of a speedometer embodying this invention.

Figure 2 is a rear view of the same.

15 Figure 3 is a diametral section taken as indicated at line 3—3 on Figure 1, but on a larger scale.

Figure 4 is a detail section taken as indicated at line 4—4 on Figure 3, but on the same scale as Figure 2.

20 Figure 5 is a detail section taken as indicated at line 5—5 on Figure 3, but also on the same scale as Figure 2.

The speedometer embodying this invention is intended primarily as an inexpensive model 25 adapted for use on bicycles. As shown in the drawing, the rotating element includes an annular magnet, 1, having the usual gap at 1^a between its poles and mounted on a pressed brass hub, 2, whose marginal portion is doubled back upon itself 30 at 2^a, and then extended in an annular flange, 2^b, which fits snugly into the central opening in the magnet, 1. The magnet is thus seated against the shoulder formed by the doubled portion, 2^a, and is held frictionally on the flange, 2^b, whose outer edge may be peened over at points, 2^c, to 35 effect a permanent securement. The web of the hub member, 2, is similarly secured to the end of a shaft member, 3, formed with an enlargement, 3^a, which provides a shoulder against which the 40 web of the pressed hub is held by peening over the extreme end of the shaft member at 3^b. The shaft is formed with a bore, 3^c, extending inwardly from the other end. For a portion of the length of this bore, 3^c, the shaft is constricted 45 at 3^d, to form a squared socket, 3^e, for interengagement with the terminal of a flexible drive shaft in a well-understood manner. The enlargement, 3^a, also provides a stop shoulder, tending 50 to check endwise movement of the shaft in its bearing sleeve, 4, which is fixed centrally in the back of the casing, 5, and at the opposite end the shaft is reduced to receive a thrust washer, 6, and a collar, 7, the washer, 6, engaging against a shoulder, 4^a, in the counterbored outer end of 55 the bearing, 4. Limited endwise play of the shaft

in its bearing is provided to ensure easy running. Preferably, for lightness, the casing, 5, is formed of thin sheet metal, such as aluminum or aluminum alloy, and to reinforce the back wall it may have radial ribs, 5^a, formed at one side of the axis, 5 the area at the other side being left plain so that a flat bracket arm, 8, may be secured thereto by rivets, 9, to provide mounting means for the instrument. The ribs, 5^a, merge with a centrally offset portion, 5^b, and the aperture at the center 10 of this area is reinforced by washers, 5^c, between which the material of the casing is clamped when the washers are secured onto the reduced and shouldered end of the bearing member, 5, by peening over the extreme end portion, 4^c, against 15 the inner washer.

The casing is also reinforced by the stiffening effect of a field cup, 10, of magnetic metal, having radial lugs, 10^a, which are fastened permanently to the back wall of the casing, 5, by rivets, two of 20 which may be the same rivets, 9, which secure the bracket arm, 8. The field cup, 10, encloses the drag element, 12, which may be an aluminum 25 disk with a peripheral flange, 12^a, and which is accommodated in the space between the magnet, 1, and the field cup, 10. The drag element, 12, is carried on a spindle, 13, having a pointed end journaled in a jewel bearing, 14, in the end of the shaft, 3, and also journaled in a bushing, 15, carried at the center of the field cup, 10. The 30 disk, 12, is provided with a hub, 16, which is forced onto a knurled portion, 13^a, of the shaft, 13. To check the drag element, 12, at its zero 35 position this part, 12, has a lug, 12^b, bent forwardly to engage the lug, 10^d, bent back from the outer surface of the field cup, 10.

A biasing spring, 17, is secured to a suitable collar, 18, fast on the spindle, 13, and the outer end of the spring is anchored in a perforated lug, 10^b, upstanding from the field cup, 10, to receive a wedge pin, 10^c. A hand or needle, 19, is secured to the end of the spindle, 13, by frictional engagement of its hub therewith.

The dial plate, 20, is formed with an annular flange, 20^a, and a short outwardly extending 45 peripheral flange, 20^b, dimensioned to fit respectively within the cylindrical wall of the casing, 5, and against its forward edge. A lug, 20^c, engages a notch, 5^e, in the casing edge to definitely fix the dial against rotation. The cover glass, 21, is fixed 50 in the re-entrant bead, 22^a, of a bezel ring, 22, which has a rearwardly extended skirt, 22^b, fitting telescopically over the cylindrical casing, 5. A spacer ring, 23, is fitted between a shoulder, 22^c, of the bezel member and a flange, 20^b, of the 55

dial, thus limiting the extent to which the skirt portion, 22^b, telescopes over the casing, 5, and firmly retaining the dial plate, 20, in its proper plane. The edge of the glass, 21, is lodged against a rubber gasket or sealing ring, 24, disposed in the channel of the bezel ring, 22, and the glass is retained by a metallic ring, 25, of angular cross-section, forced into the bezel ring and overhanging the inner edge of the glass, 21, with a paper gasket, 27, interposed as seen in Figure 3. This mounting of the glass, 21, in the bezel ring, 22, is independent of the other casing elements and can be completed before the ring, 22, is applied to the casing, 5. In the portion of the skirt, 22^b, which does not overlap the casing, 5, a slot or window, 22^a, may be formed to admit light to the face of the dial plate, 20, and a terminal cover, 26, of celluloid or the like may be secured over this opening to exclude dust. Thus, provision may be made for illuminating the dial at night by rays from a special window in the vehicle headlight (not shown) or from a special small electric lamp bulb (not shown) near the window, 25, but shielded so as not to glare into the eyes of the rider.

As seen in Figures 3 and 5, a temperature compensating shunt member, 30, is lodged between the poles, 4^a, of the magnet, 4; this element is composed of a nickel steel alloy having an automatic compensating effect for temperature changes in an understood manner.

While there is shown and described herein certain specific structure embodying the invention, it will be manifest to those skilled in the art that various modifications and re-arrangements of the parts may be made without departing from the spirit and the scope of the invention, and that the same is not limited to the particular form herein shown and described, except in so far as indicated by the appended claims.

We claim:

1. In a magnetic speedometer, a rotary shaft, an annular magnet fixed thereto, a bearing sleeve for the shaft, a casing of light sheet metal having a central aperture into which said sleeve is secured, and a field cup of magnetic metal concentrically enclosing said magnet within the casing, said cup having outwardly extending portions at the edge of its cup form, and means securing said portions to the back wall of the casing to stiffen it.

2. In a magnetic speedometer, a rotary shaft, an annular magnet fixed thereto, a bearing sleeve for the shaft, a casing of light sheet metal having a central aperture into which said sleeve is secured, said casing being formed with an annular boss around said aperture with radial ribs extending therefrom and pressed into the back wall of the casing to stiffen it.

3. In a magnetic speedometer, a cylindrical casing of light sheet metal, a dial plate stepped upon the edge of said casing and a bezel ring with a deep annular flange telescopically engaging the casing, said bezel having an offset forming a shoulder opposite said edge of the casing and a spacer interposed between said dial and the shoulder, the outer edge of the bezel forming an inturned bead, a cushion ring in said bead, a

cover glass lodged against the cushion and a retaining ring of angular cross-section encircling the edge of the glass and frictionally held in the cylindrical wall of the bezel between said bead and the plane of the shoulder to retain the glass independently of the dial and casing.

4. In a magnetic speedometer, in combination a rotary shaft, an annular magnet fixed thereto, a journal bearing for the shaft, a cup-form casing of sheet metal secured to said journal bearing at the center of its transaxial web and having its cup flange encompassing the magnet, a cup-form drag element and a spindle fixedly secured at the center thereof and mounted with the spindle, stepped in the end of the magnet shaft and with the drag cup hooding the magnet, a cup-form field member hooding the drag element and magnet and made fast to the web of the cup-form casing by portions extending radially outward from its cup-form, annular disks embracing the web of the cup form casing at the fixed securement thereof to the journal bearing to reinforce the web, said web being formed with a plurality of radial embossments angularly distributed in an arcuate portion of its area between said reinforcing disks and the securement of the cup-form field member to the web, whereby the web of the casing is stiffened against vibration due to jar of the instrument on a road vehicle.

5. In a magnetic speedometer, in combination a rotary shaft, an annular magnet fixed thereto, a journal bearing for the shaft, a cup-form casing of sheet metal secured at the center of its transaxial web to the journal bearing, a cup-form drag element and a spindle fixedly secured thereto at the center of the cup form of the drag element, the spindle being stepped in the end of the magnet shaft with the drag cup hooding the magnet, a cup form field member hooding the drag element and magnet and made fast to the casing by means extending radially outward from its cup form to stiffen said casing, the transaxial web of the drag element having an abutment protruding toward the web of the field cup and the web of the field cup having an abutment protruding toward the web of the drag element, said abutments being positioned in said webs respectively for encounter with each other in the rotation of the drag element about its axis.

6. In a magnetic speedometer, a cylindrical casing with a dial plate, a cover glass, a bezel ring for the cover glass having an inturned portion bearing against the outer marginal portion of the glass with a cushion ring interposed and a retaining ring fitted into said bezel ring against the opposite side of the glass and frictionally held in the bezel, said bezel ring having a deep annular flange telescopically engaging the casing and having an offset forming a shoulder opposite the marginal portion of the dial plate, and a spacer interposed between said dial and the shoulder, the bezel ring having a window in its annular flange opposite the space between said dial plate and shoulder, and the spacer being interrupted at said window.
